UNITED STATES PATENT OFFICE.

HERBERT D. DREYFUS, OF TERRE HAUTE, INDIANA.

SAFETY DEVICE FOR MOTION-PICTURE PROJECTORS.

1,342,429.

Specification of Letters Patent.

Patented June 8, 1920.

Application filed August 9, 1919. Serial No. 316,304.

To all whom it may concern:

Be it known that I, HERBERT D. DREYFUS, a citizen of the United States, residing at Terre Haute, in the county of Vigo and State 5 of Indiana, have invented a new and useful Safety Device for Moving-Picture Projectors, of which the following is a specification.

The object of my invention is to produce 10 a device by which breakage or non-feed of the film in a motion picture projector will automatically screen the film from the projecting light and discontinue the driving action upon the film.

15 The accompanying drawings illustrate my invention. Figure 1 is a side elevation, rather diagrammatic in character, of an embodiment of my invention in conjunction with adjacent parts of the projector; Fig. 2 20 a plan, in partial horizontal section, of the parts shown in Fig. 1; and Fig. 3 an end elevation of the plunger-releasing mechanism.

In the drawings, 10 indicates the usual light-tube of lamp 11; 12 the film-driving 25 gear advanced step by step by motor train 13, driven, in the present instance, by electric motor 14, in the usual manner; 15 the take-off film-driving gear driven by train 13; 16 the loop-setter arm carried by shaft 30 17 having cam 18 which controls clutch arm 19 acting upon clutch member 20 which cooperates with clutch-member 21 carried by pulley 22 connected by belt 23 with the take-up drum (not shown). A so-called "loop" 25 of film is thus normally maintained between the gears 12 and 15, around finger 16. In Fig. 1, the loop referred to is directly suspended from wheel 15 and an idler 75, but it will be readily understood that the precise manner in which the loop is obtained and sustained is not material. All of the above parts are well known, as shown, in one well-known type of machine, and have their counter-parts, either as part of, or readily 40 addable to, other types of machines.

Pivoted at 25 on tube 10, is a shutter 26 gravity-urged to position to cover the end of tube 10 and normally held in open position by a spring catch 27 engaging arm 28. 45 Arranged in the path of movement of arm 28 is a plunger 29 urged in one direction by spring 30 and retained in retracted position by a catch lever 31 which takes into a notch formed across the plunger, as indicated by dotted lines, Fig. 3. Plunger 29, in its retracted position, holds a spring terminal 32

in contact with terminal 33 and these two terminals are arranged in the circuit of motor 14.

Lever 31 is connected by link 34 attached 60 to arm 35 of the armature 36 of electromagnet 37, said armature, in the form shown, being a rotary armature.

Referring now to Figs. 1 and 2, 40 is a frame, or plate, suitably formed as a support for a pivoted gravity arm 41, carrying a roller 42 adapted to rest lightly on film 43, conveniently just beyond take-up wheel 15, so as to hold spring connector 44 out of contact with terminal 45. Terminals 45 70 and 45' are connected with the coil of magnet 37 and an energizing circuit in any well-known manner, to control the action of the magnet. The action of the magnet is also controlled by terminals 46 and 47 one of 75 which is conveniently attached to arm 19 and the other to frame 40, the arrangement being such that magnet 37 will be energized whenever loop-setter 16 is moved to an abnormal position, due to improper loop conditions, sufficient not only to separate clutch member 20 from clutch member 21, but further to bring terminal 46 into contact with terminal 47.

The operation is as follows: The film is 80 threaded through the machine in the usual manner, as shown in Fig. 1, and with roller resting lightly thereon so as to hold connector 44 out of contact with terminals 45 and 45'. Loop-setter 16 is held by film 43 in 85 position to hold arm 19 so that terminal 46 is out of contact with terminal 47 and clutch member 20 in engagement with clutch member 21. Shutter 26 is swung to open position and thereby pushes plunger 29 to position to hold terminal 32 in contact with terminal 33. Thereupon motor 14 may be started by operating switch 50. So long as the film movement is normal the parts will remain in the positions stated, except that, 90 from time to time, loop-setter 16 may rise enough to withdraw clutch member 20 from member 21, so as to temporarily stop wheel 15 and permit wheel 12 to accumulate a proper loop in film 43 at setter 16. If, however, anything should happen to the film, at 95 or above wheel 12, which stops its proper advance across the light beam, wheel 15 will continue its take-up movement so as to sharply draw setter 16 upwardly and bring terminal 46 into contact with terminal 47 thus energizing magnet 37 so that catch 31

is withdrawn from plunger 26, whereupon said plunger withdraws from terminal 32, permits said terminal to break the circuit of motor 14, and drives against arm 28 so as to move it from catch 27 and permits shutter 26 to drop over tube 10.

In case the film breaks between the take-up wheel 15 and the storage roll, arm 41 will drop, causing connector 44 to bridge terminals 45 and 45', thus closing the circuit of magnet 37 and causing motor 14 to stop and shutter 26 to drop, as already described.

I claim as my invention:

1. In a projector, the combination of 15 film - driving mechanism, loop - supporting means associated therewith, a finger movably supported in said loop, a lever connected with and movable by said finger, a clutch forming part of the film-driving train, connections between said lever and clutch, a pair of coöperating electric terminals one of which is carried by said lever, an electromagnet in circuit with said terminals, a light-ray-producer, a light-ray-obstructor adapted to obstruct the passage of the light to the film, and means controlled by the electromagnet for causing said light-ray-obstructor to move to obstructing position when the electromagnet is energized.

2. In a projector, the combination of 20 film - driving mechanism, loop - supporting means associated therewith, a finger movably supported in said loop, a lever connected with and movable by said finger, a clutch forming part of the film-driving 25 train, connections between said lever and clutch, a pair of coöperating electric terminals one of which is carried by said lever, a second pair of electric terminals, a movable arm associated with said terminals and adapted to rest upon the film beyond the driving mechanism, an electromagnet in circuit with said terminals, a light-ray-producer, a light-ray-obstructor adapted to obstruct the passage of the light to the film, and means controlled by the electromagnet for causing said light-ray-obstructor to move to obstructing position when the electromagnet is energized.

In witness whereof I have hereunto set my hand at Indianapolis, Indiana, this sixth day of August, A. D. one thousand nine hundred and nineteen.

HERBERT D. DREYFUS.
